Application July 10, 1935, Serial No. 30,589
In Great Britain July 13, 1934

2 Claims. (Cl. 11—1)

The present invention relates to improvements in or connected with bookbinding, particularly to machines of the type described in my prior United States Patent No. 982,438 for Bookbinding machine, granted January 24, 1911, which discloses a machine suitable for carrying out the operation known as lining in the trade of bookbinding in conjunction with a rounding and back-
ing machine.

10 In the manufacture of some classes of books it is usual to attach tapes to the backs of the books during the sewing operation. This method of attaching the tapes has certain disadvantages, namely, the attachment is usually so loose that
15 the tapes require to be subjected to an additional hand- or machine-operation of pasting their ends to the sides of the books in order to make them secure from displacement during the subsequent bookbinding operations. Subsequent to the past-
20 ing down of the tapes the backs of the books are coated with glue to ensure adhesion between the signatures of the book and as the glue cannot be fully worked in below that area of the backs of the books which is covered by the tapes the full
25 strength of the book back is thus unattainable by this method.

Further, the top surfaces of the tapes are saturated with this glue and they may dry in a wrinkled condition and dry very hard before the
30 rounding and backing operations are performed and thus render such operations much more difficult and destructive to the tapes.

The aforesaid disadvantages can be avoided by delivering the tapes from spools to the glued
35 backs of the books subsequent to the rounding and backing operations and simultaneously with the application of the scrim or crash or first lining.

My invention resides in an improved arrangement by which reels of much greater length than
40 the width of the tapes and consequently containing large quantities of tapes can be used and the tapes delivered to the scrim at a constant position in relation to the book despite the fact that the tapes will be delivered from constantly chang-
45 ing portions of the reels.

In those book-binding machines in which the backs of the books are held uppermost in the various operations the tapes will be fed on the under-side of the scrim or crash and applied simultaneously to the book back. In those machines in which the books are held back lowermost the tapes will be fed to the books on the upper-side of the scrim or crash and applied simultaneously to the book back.

50 The accompanying drawings illustrate dia-

grammatically an arrangement in accordance with the invention for feeding the tapes simultaneously with the scrim or crash to the already glued backs of books, the means (not shown) for applying the scrim to the backs of the books being assumed to be similar for instance to that shown in Figs. 8 and 9 of my said prior patent and serving also to apply the tapes to the backs of the books in the same operation. Fig. 1 is a front elevation, Fig. 2 a plan view and Fig. 3 an end elevation of an arrangement of the feeding mechanism suitable for feeding four spaced tapes from reels of greater length than the width of the tapes, and containing a large quantity of tape, to the backs of books simultaneously with the scrim. Fig. 4 is a detail to enlarged scale of the tape guiding mechanism shown in Figs. 1 to 3, and Fig. 5 is a plan view of Fig. 4.

Throughout the several figures of the drawings only those parts of the machine disclosed in my prior Patent No. 982,438 which are necessary for an understanding of the present invention are shown and described.

In the drawings, 1 denotes the table of the machine, 2 the scrim or crash roll from which the scrim or crash is led over the guide or tension rods 3, 3' to the scrim feed rolls 4, 4' whence it is passed over the glued backs of the books such as 5, is severed, and applied thereto say as described in my said prior patent. In my invention tapes are fed to the backs of the books and applied thereto simultaneously with the scrim or crash and subsequent to the rounding and backing operations on the books if such operations are carried out. To this end there are associated with the scrim roll, tape reels from which tapes are fed to the backs of the books at the same time as and by the same feed rolls 4, 4' as those feeding the scrim or crash and are severed and applied to the books simultaneously with the latter.

In the arrangement shown, which, as stated, is adapted for use with reels containing large quantities of tape wound on reels of much greater length than that of the tape and therefore delivered from constantly changing portions of the reels, auxiliary guide means is provided for ensuring that the tapes thus led from the reels will pass under the scrim at a constant position in relation to the book. In the particular form shown four sets of tapes 10 are supplied with the scrim.

As shown, the table 1 is fitted with two reel supporting frames each denoted generally by the reference numeral 12, and each consisting of a bracket 13 bolted to the table and provided with

a pair of reel supporting spindles 14 in superposed parallel relation and pairs of guide rods 17, 17', the reels 10 being disposed in planes at right angles to the plane containing the axis of 5 the scrim feed rollers 4, 4'. In order to permit easy removal and replacement of the tape reels 10 they are held on the spindles 14 by means of pivoted arms 15 formed with hook slots 16 adapted to engage reduced portions of the reel 10 spindles 14. One of said arms 15 is shown in Fig. 1 both in full lines in locking position and in dotted lines in a raised position permitting lateral withdrawal of the reel from its spindle.

In order to ensure satisfactory feed of the 15 tapes 10 from the point from which they leave the reels and in which they extend at right angles to the scrim, into a position in which they move parallel with the scrim, there are mounted on bearing brackets 6 secured to the 20 table 1 and beneath the scrim roll 2 superposed guide rods 18, 18' from which the tapes pass upwards to the scrim feed rolls 4, 4' and on these guide rods 18, 18' are carried spaced bracket arms 19, 19', 20, 20', on the ends of each of 25 which are mounted guide rollers 21 with vertical axes at such heights as to ensure a quarter turn of the separate tapes as they pass to the guide rollers 21 and to ensure a further quarter turn as they pass around the guide rods 18, 18' 30 to the feed rolls 4, 4' for the scrim.

The arms 19, 19', 20, 20' may be displaced on the rods 18, 18' as desired and clamped in any desired position by means of the split clamp 35 shown in Figs. 4 and 5 in order to provide any desired spacing of the tapes.

The tapes are guided from the reels over the 40 rollers 21 to the guide rods 18, 18' and thence to the feed rolls 4, 4' passing between them under the scrim so that when they are severed into lengths and applied to the backs of books such as that 5 shown the tapes will lie between the back of the book and the scrim.

I claim:—

1. In a bookbinding machine in combination with scrim rolls and feed rolls for feeding the scrim to the back of the books, means for delivering a plurality of relatively narrow tapes with the scrim to the feed rolls and to the back of the books in a constant position in relation to the width of the scrim from a plurality of relatively wide tape reels affording supplies of tape, said means including a plurality of tape reels in spaced relation, said reels disposed with their axes at right angles to the axis of the scrim roll, a plurality of guide rollers for receiving the tapes from said reels, said guide rollers spaced from one another along the width of the 15 scrim with their axes at right angles to the axes of the reels, and guide rods disposed parallel with the feed rolls receiving tapes from the guide 20 reels and delivering the tapes to the feed rolls.

2. In a bookbinding machine in combination with scrim rolls and feed rolls for feeding the scrim to the back of the books, means for delivering a plurality of relatively narrow tapes with the scrim to the feed rolls and to the backs 25 of books in a constant but changeable position in relation to the width of the scrim from a plurality of relatively wide tape reels affording supplies of tape, said means including a plurality of tape reels in spaced relation, said reels disposed with their axes at right angles to the axis of the scrim roll, a plurality of guide rollers for receiving the tapes from said reels, said guide rollers spaced from one another along the width 30 of the scrim with their axes at right angles to the axes of the reels, and guide rods disposed parallel with the feed rolls receiving tapes from the guide 35 reels and delivering the tapes to the feed rolls. 40

JOHN MURRAY.
